UNITED STATES PATENT OFFICE.

DUDLEY S. SEYMOUR, OF OAK PARK, ILLINOIS, ASSIGNOR TO UNION SPECIAL MACHINE COMPANY, OF CHICAGO, ILLINOIS, A CORPORATION OF ILLINOIS.

SEWING-MACHINE.

1,295,074.

Specification of Letters Patent. Patented Feb. 18, 1919.

Application filed February 7, 1916. Serial No. 76,685.

To all whom it may concern:

Be it known that I, DUDLEY S. SEYMOUR, a citizen of the United States, residing at Oak Park, in the county of Cook, State of Illinois, have invented certain new and useful Improvements in Sewing-Machines, of which the following is a description, reference being had to the accompanying drawing and to the figures of reference marked 10 thereon.

The invention relates to new and useful improvements in sewing machines, and more particularly to a sewing machine wherein the material being stitched is supported by 15 a work supporting arm extending at an angle to the plane of the overhanging arm of the machine.

An object of the invention is to provide a machine of the above character with a horizontal arm supported by the standard on which is carried the work supporting arm proper, and in which horizontal arm is mounted the main shaft of the machine, suitable devices being operated by said main 25 shaft for actuating the needle and the complementary stitch forming mechanism.

Another object of the invention is to provide a machine of the above character wherein the needle may be reciprocated by an oscillating shaft in the overhanging arm which in turn is oscillated by the main shaft.

A further object of the invention is to provide a machine of the above character having an oscillating shaft for reciprocating the 35 needle with a thread laying device which is also oscillated by said shaft in the overhanging arm.

A still further object of the invention is to provide a machine of the above character 40 having a shaft in the overhanging arm for oscillating the needle and the thread laying device with a trimmer wherein the movable blade operates in a horizontal plane, and said blade is oscillated through a train of connections actuated by said oscillating shaft in the overhanging arm.

A still further object of the invention is to provide a machine of the above character 45 having the main shaft in the horizontal arm with the looper and the feeding device which are carried by the work supporting arm proper and which are actuated by said main shaft in the horizontal arm.

These and other objects will in part be

obvious and will in part be hereinafter more 55 fully described.

In the drawings, which show by way of illustration one embodiment of the invention:

Figure 1 is a view in side elevation showing a machine embodying my improvements;

Fig. 2 is a front view of the same;

Fig. 3 is a plan view of the same;

Fig. 4 is a sectional view on the line 4-4 of Fig. 2;

Fig. 5 is a vertical sectional view through the horizontal work supporting arm and the supporting post showing the main driving shaft and the manner of supporting the same; also the devices for operating the 70 looper and feed;

Fig. 6 is a side view on an enlarged scale, showing the end of the work supporting arm and the end of the overhanging arm, the face plate being removed to show the operating 75 mechanism;

Fig. 7 is a vertical sectional view through the forward end of the overhanging arm showing particularly the manner of mounting the rock shaft which operates the thread 80 laying hooks and the trimmer;

Fig. 8 is a detail, partly in section and partly in plan, showing the presser foot, the trimmer blades, the thread laying hooks, the thread guiding member and the needles;

Fig. 9 is a detail view in front elevation showing the needles, the thread hooks, a portion of the presser bar, the supporting sleeve for the thread hooks, the stationary thread guide and the movable trimmer blade;

Fig. 10 is a detail in vertical section showing the sleeve for operating the thread hooks, the manner of supporting the same, and the actuating eccentric and coöperating strap for oscillating the trimmer;

Fig. 11 is a view, partly in section and partly in plan, on the line 11-11 of Fig. 6;

Fig. 12 is a view, partly in section and partly in plan, on the line 12-12 of Fig. 6;

Fig. 13 is a sectional view on the line 100 13-13 of Fig. 6;

Fig. 14 is a detail, partly in section and partly in side elevation, showing a portion of the presser bar, a portion of the auxiliary guiding bar therefor, and the manner of 105 placing said presser bar under tension without interfering with the oscillations of the guide bar;

Fig. 15 is a view, on an enlarged scale, showing the thread hooks, the stationary thread guide, the needles, the fabric, and a series of stitches formed therein, the thread hooks being disengaged from the threads;

Fig. 16 is a similar view, showing the thread hooks at the forward end of their stroke;

Fig. 17 is a longitudinal sectional view 10 through the work supporting arm and the depending post carrying the same, showing the operating mechanism for the feed dogs and also the operating mechanism for the looper;

Fig. 18 is a horizontal sectional view 20 through the upper part of the work supporting arm, showing in plan the throat plate, the feed bar, the looper supporting shaft and the devices for operating the same;

Fig. 19 is a detail in vertical section through the work supporting arm showing the means for controlling the operation of the auxiliary feed bar;

Fig. 20 is a sectional view on the line 20—20 of Fig. 19;

Fig. 21 is a sectional view on the line 21—21 of Fig. 19; and

Fig. 22 is a sectional view of the upper 30 part of the standard and the projecting arm carried thereby showing the manner of oscillating the shaft in the overhanging arm from the main shaft in the horizontal arm.

The machine embodying my invention consists broadly of a supporting standard from which projects an overhanging arm carrying the needle bar and needle, also the thread laying device which co-operates 40 with the needle and the trimmer which trims the fabric in advance of the stitching point. These parts are operated by an oscillating shaft located in said overhanging arm. The standard also carries a forwardly projecting arm on which is mounted a horizontal arm carrying the main shaft, said main shaft extending through the projecting arm on the standard, and carrying a belt wheel on its outer end. At the free 50 end of the horizontal arm there is a supporting post on which is mounted the work supporting arm proper. This work supporting arm is arranged at an angle to the plane of the overhanging arm and has its 60 free end extending underneath the free end of the overhanging arm. A looper operates with the needle and is located in said work supporting arm. Feeding devices are also located in the work supporting 65 arm. These feeding devices and the looper are operated from the main shaft located in said horizontal arm.

Referring more in detail to the drawings, my improved machine consists of a supporting standard 1 having a suitable base 2 by

which the same is secured to a table. Said standard 1 at its upper end is provided with a laterally projecting arm 3. A shaft 4 is mounted in suitable bearings in this overhanging arm and extends into the 70 standard. Projecting laterally from the standard and forwardly from the standard is a supporting arm 5 which carries a horizontal arm 6. This horizontal arm is substantially parallel with the overhanging 75 arm 3. At the outer end of the horizontal arm 6 there is a depending post 7, and this depending post carries at its lower end the work supporting arm 8. Said work supporting arm 8 extends at an angle to a vertical plane containing the longitudinal center of the overhanging arm, that is, the plane of the overhanging arm, and the free end of this work supporting arm 8 terminates underneath the outer end of the overhanging arm 3.

Mounted in the horizontal arm 6 is a main shaft 9. This main shaft extends through a bearing 10 at one end thereof and through bearings 11 and 12 adjacent the other end thereof. Said shaft projects through the arm 5 and is provided with a belt wheel 13. Said shaft 9 is formed with a crank 14 and a pitman 15 co-operating with the crank oscillates the shaft 4 in the overhanging arm. Said shaft 4 has a depending arm 16 to which the pitman 15 is connected by suitable means.

Mounted in the outer end of the overhanging arm 3 is a needle bar 17. An arm 18 is mounted on the outer end of the shaft 4, and this arm 18 is connected by a link 19 to a suitable lug carried by a collar 20 fixed to the needle bar. Said arm 18 is formed with a counterweight 21, which 100 counterbalances the parts operated by the arm 19 and prevents unnecessary vibrations when the shaft 4 is oscillated rapidly.

At the lower end of the needle bar 17 there are two pairs of needles 22 and 23. These pairs of needles are staggered relative to each other, as clearly indicated in Fig. 8 of the drawings. The material to be stitched is held on the work supporting arm 8 by a presser foot 24 which is mounted on the lower end of a presser bar 25, and this presser bar is in turn mounted to slide in suitable bearings in the overhanging arm 3. The presser foot is provided with suitable needle slots 26 and 27 which receive respectively the pairs of needles 22 and 23.

Co-operating with each pair of needles is a thread laying mechanism which lays a thread back and forth so that it is secured to the fabric being stitched by the needle threads. Referring to Figs. 15 and 16, there are shown two fabric sections A and B, the edges of which have been trimmed and abutted at C. The needles 22—22 carry threads *a*—*a*, while the needles 23—23 carry threads *b*—*b*. The 120 125 130

cross threads for the needles are guided by a fixed thread guiding arm 28, said arm having a thread eye 29 through which the thread *c* passes and a second thread eye 30 through 5 which a thread *d* passes.

There are two thread hooks 31 and 32. The thread hook 31 as it moves forward engages the thread *c* and positions the same, as shown in Fig. 16, so that the left hand needle 10 22 will pass between the strands of the loop formed by the thread hook 31, while the right hand needle 22 passes in front of said thread. This causes the thread *c* to be stitched down by the needle threads *a*—*a* and to be 15 woven back and forth passing around the needle threads at each needle puncture, as clearly shown in Fig. 15. The thread hook 32 co-operates with the needles 23. This thread hook engages the thread *d* and operates there- 20 on in precisely the same manner as above described in connection with the hook 31. The thread hooks 31 and 32 are carried by a supporting arm 33. Said arm has an enlarged head 34 at its lower end and the 25 thread hooks are separately connected thereto so that they may be properly adjusted. Said supporting head 34 is provided with thread guiding eyes 35 and 36 through which the threads *c* and *d* pass respectively.

30 The fixed thread guiding arm 28 is attached to the overhanging arm by suitable means. The supporting arm 33 is carried by a collar 37 which is rigidly secured to a sleeve 38, see Fig. 10. The sleeve 38 is 35 mounted on the presser bar 25. The opening in the overhanging arm at the lower end for the presser bar, as shown in this figure, is enlarged so as to permit the sleeve 38 to extend down through the opening. Said sleeve 40 is formed with a shoulder 39 which rests on the upper face of the lower bearing of the presser bar.

The sleeve 38 is formed with a projecting arm 40, see Fig. 13. This sleeve is oscillated 45 by a rock lever 41 which has a depending arm 42 carrying a ball stud 43 and a link 44 engaging this ball stud also engages a ball stud 45 on the outer end of the arm 40. The rock lever 41, as shown in Fig. 7, is mounted 50 on cone bearings 46 and 47 carried by a supporting rod 48 which extends through a portion of the overhanging arm and is rigidly secured thereto by a clamping nut 48'. The other arm 49 of the rock lever 41 is connected by a link 50, see Fig. 6, to an arm 51 mounted on the shaft 4. The oscillations of the shaft 4 will rock the lever 41 and this will, through the link 44, oscillate the sleeve 38 which will in turn oscillate the supporting 55 arm 33 and the thread hooks carried thereby.

In order to trim the edges in advance of the stitching, I have provided a trimming mechanism which includes a fixed trimming blade 52 and a movable trimming blade 53. 60 The fixed trimming blade is mounted on the

presser foot 24 while the movable trimming blade 53 is carried by an arm 54. The arm 54 swings about a vertical axis and the trimming blade 53 moves in a horizontal plane. This trimming mechanism operates to trim 70 the edges of the fabric sections after which they are abutted, as referred to above.

The arm 54 carrying the trimmer blade is fixed to the lower end of the auxiliary guiding bar 55. This auxiliary guide bar operates to guide the main presser bar 25 and prevent the same from oscillating. This is accomplished by an arm 56 which is fixed to the presser bar 25 by a set-screw 57. Said arm projects rearwardly and is provided 80 with an opening 58, see Fig. 14, through which the auxiliary guiding bar 55 freely passes. The arm 56 is formed in its upper face with a circular channel 57 into which extends an inverted cup 58. This channel 85 fits the cup loosely. A spring 59 encircles the auxiliary guide bar 55 and rests at its lower end on the upper face of this cup. A threaded sleeve 60 extends through the upper bearing 61 for the auxiliary guide bar 55 90 and the spring 59 at its upper end bears against this threaded sleeve 60. By turning the sleeve down or up, the tension of the spring on the arm 56 may be varied. This spring 59 places a tension on the presser 95 bar, that is, normally holds the presser bar against the work support. The auxiliary guide bar 55 not only passes freely through the arm 56, but also through the inverted cup 58 and the sleeves 60 so that it is free from 100 any endwise pressure and may also oscillate freely in these parts. A spring 62 encircles the auxiliary bar 55 and bears at its lower end against the arm 54. The upper end of this spring 55 bears against a washer 63 in a 105 recess in the lower face of the lower bearing 64 for the auxiliary guide bar. This spring 62 normally forces the guide bar 55 downwardly and holds the movable trimming blade 53 in contact with the stationary trim- 110

The auxiliary guide bar 55 is provided with a collar 65 which carries an arm 66, see Fig. 11. An eccentric 67 is fixed to the upper end of the sleeve 38. An eccentric strap 115 68 co-operates with this eccentric and engages a ball stud 69 at the outer end of the arm 66. This eccentric 67 is in the form of a segment of a sphere and, therefore, the auxiliary bar 55 may have a limited movement 120 in a vertical direction without interfering with the connection with said eccentric. This permits the presser foot to be raised and lowered and the movable trimmer blade to maintain its operative position relative to 125 the presser foot.

From the above description, it will be apparent that the shaft 4 located in the overhanging arm through the arm 18 reciprocates the needle arm 17 and through the arm 130

51 and the rock lever 41 oscillates the sleeve 38. The oscillations of this sleeve 38 are imparted directly to the thread laying hooks and through the eccentric 67 said oscillations 5 impart movement to the auxiliary presser bar and thus to the movable trimming blade.

The main shaft 9 projects into the supporting post 7 and carries actuating devices for the looper and for the feeding mecha-

10 nism. As herein shown the horizontal arm 6 has an overhanging portion 70, while the post 7 is provided with a laterally projecting portion 71. These parts 70 and 71 are formed with projecting lugs 72, and suitable 15 bolts 73 pass into the lugs and secure the sections together, and in this manner the post 7 with the work supporting arm proper is carried by the horizontal arm 6. This construction is shown in detail in Figs. 2 and 4.

20 The looper 74 coöperates with the front pair of needles 22, while the looper 75 co- operates with the rear pair of needles. These loopers are mounted on a looper carrier 76, see Fig. 17, and the looper carrier is

25 fixed to a looper supporting shaft 77. This looper supporting shaft 77 is mounted in suitable bearings 78 and 79 so that the shaft may not only oscillate but be moved endwise in the bearings. The looper supporting shaft

30 77 is oscillated by a train of mechanism connected to the main shaft 9 in the horizontal arm 6. Said train of mechanism consists of an arm 80 carried by a collar 81 fixed to the shaft, a rock shaft 82 which carries an arm 83 35 and this arm 83 is connected to the arm 80 by a link 84. The arms 80 and 83 are formed with ball studs so that the shaft 77 may have an endwise movement without disturbing its connection with the rock shaft 82. The rock

40 shaft 82 is provided with a second arm 85 carrying a ball stud and an eccentric strap 86 coöoperating with an eccentric 87 on the main shaft 9 engages this second arm 85. As the main shaft 9 rotates, the eccentric 87 will 45 oscillate the rock shaft 82, and this in turn through the arms 80 and 83 and the connecting link 84 will oscillate the looper shaft.

The looper shaft is moved endwise by a sleeve 88. Said sleeve is freely mounted on 50 the shaft and is located between fixed collars 89 and 90. This permits the shaft to oscillate in the sleeve, but any endwise movements of the sleeve will be imparted to the shaft. Said sleeve 88 has a downwardly 55 projecting fin 91 which extends between guide plates 92 and holds the sleeve from oscillating. The sleeve 88 is given an endwise movement by a rock shaft 93. Said rock shaft has a downwardly projecting slotted 60 arm 94 and a link 95 has an adjustable connection with the slot in the arm 94 and is also connected to the sleeve 88. This shaft 93 on its other end carries an arm 96, see Fig. 18. On the outer end of the arm 96 is a 65 ball stud 97 with which an eccentric strap 98

connects. This eccentric strap 98 coöperates with an eccentric on the main shaft 9, see Fig. 5. This eccentric strap will oscillate the rock shaft 93 which will move the collar 88 endwise, and this gives the endwise movement to the looper supporting shaft.

70 For moving the work along the arm there is a main feed dog 99 which is fixed to a feed bar 100. This feed dog is so constructed as

75 to feed the work off the end of the arm. The feed bar 100 is connected to a sleeve 101 which receives an eccentric 102 fixed to the main shaft 77.

The eccentric 102 may move endwise in the sleeve or the sleeve endwise 80 on the shaft. The oscillating movements of the shaft will, however, through the eccentric raise and lower the sleeve 101.

The feed bar adjacent its rear end is supported by a cross pin 103. The cap plate 104 is formed with a recess which provides a slot 105 for 85 this pin 103.

This permits the feed bar to move endwise on the pin, but said pin serves as the fulcrum for the feed bar so that as the sleeve 101 is raised and lowered the feed

90 dog will be raised and lowered. Said feed bar is moved endwise by a link 106 which is pivotally connected at 107 to the end of the feed bar.

The other end of this link 106 is pivotally connected to a stud 108 which is 95 adjustably mounted in a slot 109 formed in an arm 110 carried by the rock shaft 93.

As this rock shaft 93 oscillates the link 106 will be moved endwise, and this will impart an endwise movement to the feed bar. The

amount of endwise movement imparted to 100 the feed bar may be adjusted by shifting the position of the stud 108 in the slot 109. Co-

operating with the main feed dog 99 is an auxiliary feed dog 111 which is carried by an auxiliary feed bar 112. The main feed

105 bar 100 is slotted lengthwise to receive this auxiliary feed bar, and said auxiliary feed bar is slidingly held in said slot by a screw 113 passing through a slot in the bar. The

auxiliary feed bar will be raised and lowered 110 in timing with the main feed bar. This auxiliary feed bar is moved endwise by a mechanism which permits it to have a differential movement relative to the main feed bar.

115 Mounted in the work supporting arm 8 is a U-shaped lever 114. The feed bars and the looper shaft pass between the arms of this U-shaped lever. Said U-shaped lever is mounted to oscillate on a supporting pin 115.

The arm 116 of said U-shaped lever is 120 connected at its upper end to a link 117, and this link is in turn connected to the auxiliary feed bar 112. When the parts

are positioned as shown in Fig. 19, the stud 120 is substantially opposite the pivotal connection between the link 117 and the arm 116.

125 As the main feed bar moves back and forth, the link 117 will oscillate the U-shaped lever 114 and the oscillations of this U-shaped lever will, through the link 117, 130

be imparted to the auxiliary feed dog. With this stud 120 substantially opposite the pivot point between the link 117 and the arm 116, the amount of movement given to the auxiliary feed dog will be substantially the same as that imparted to the main feed dog. If this stud 120 is shifted downwardly in the slot 119, then the amount of movement imparted to the auxiliary feed bar relative to the amount of movement imparted to the main feed bar will be increased. The link 121 may be shifted by a hand lever 123 which is connected by a link 124 to the link 121. This hand lever may be provided with a finger piece 125 which is located outside of the work supporting arm so that the lever may be readily shifted.

It will be understood, of course, that a looper coöperates with each pair of needles, the needle loops beneath the sections of fabric being joined being connected by the looper threads. The abutted edges of the fabric sections are, therefore, joined by the cross threads on the upper face of the fabric and the looper threads on the lower face of the fabric.

From the above description it will be apparent that I have provided a sewing machine having a suspended work supporting arm located at an angle to the plane of the overhanging arm, and the fabric sections being stitched are fed off from the end of this work supporting arm. The main shaft for operating the parts is located in the horizontal arm which supports this work supporting arm, and the needles, the trimmer and the thread laying devices are operated from one end of this main shaft, while the looper and feed are operated from the other end of the main shaft. This arrangement has a special advantage in the type of machine where there is a forwardly projecting arm carried by the standard, a horizontally disposed arm mounted on this forwardly projecting arm and in turn supporting the work supporting arm proper. In other words, between the end of the main shaft and the looper shaft there is a train of connections of substantially the same extent as the train of connections between the other end of this main shaft and the oscillating shaft which vibrates the needles and operates the other elements carried by the overhanging arm. This clearly distributes the strain on the main shaft and avoids long trains of connections which, of course, are objectionable.

The looper mechanism described above is shown, described, and claimed in my co-pending application 83,297, filed March 10, 1916. The thread laying mechanism is described and claimed in my copending application Serial No. 83,300, filed March 10, 1916. The trimming mechanism is described and claimed in my copending ap-

plication, Serial No. 83,299, filed March 10, 1916. The feed mechanism is described and claimed in my copending application, Serial No. 83,298, filed March 10, 1916.

These devices above described are, therefore, not claimed *per se* in this application, as they form no part of the present invention, except as they are elements of the combinations set forth in the appended claims. It will be understood that various changes in the arrangement of parts and modifications in the details of construction shown and described may be made without departing from the spirit of this invention as set forth in the appended claims.

Having thus described my invention, what I claim as new and desire to secure by Letters Patent, is:—

1. A sewing machine including in combination, a standard, an overhanging arm carried thereby, a needle mounted on said arm, a horizontal arm carried by said standard, a main shaft mounted in said horizontal arm, devices actuated by said main shaft for operating said needle, a work supporting arm carried by the horizontal arm and having its free end projecting underneath the outer end of the overhanging arm, complementary stitch forming mechanism mounted in said work supporting arm and devices actuated by said main shaft for operating said complementary stitch forming mechanism.

2. A sewing machine including in combination, a standard, an overhanging arm carried thereby, a needle mounted on said arm, a horizontal arm carried by said standard, a main shaft mounted in said horizontal arm, devices actuated by said main shaft for operating said needle, a work supporting arm carried by the horizontal arm and having its free end projecting underneath the outer end of the overhanging arm, complementary stitch forming mechanism mounted in said work supporting arm and devices actuated by said main shaft for operating said complementary stitch forming mechanism, a feed dog located at the free end of said work supporting arm, a feed bar supporting said feed dog and means for actuating said bar from said main shaft.

3. A sewing machine including in combination a standard, an overhanging arm carried thereby, a needle mounted on said arm, a horizontal arm carried by said standard, a main shaft mounted in said horizontal arm, devices actuated by said main shaft for operating said needle, a work supporting arm carried by the horizontal arm and having its free end projecting underneath the outer end of the overhanging arm, complementary stitch forming mechanism mounted in said work supporting arm and devices actuated by said main shaft for operating said complementary stitch forming mechanism, a main

feed dog at the outer end of said work supporting arm, a feed bar carrying the same, means for moving said feed bar up and down, devices actuated by the main shaft for moving the feed bar back and forth, an auxiliary feed dog coöperating with said main feed dog, an auxiliary feed bar supporting the same and movable up and down with the main feed bar and devices actuated by the main feed bar for operating said auxiliary feed dog.

4. A sewing machine including in combination, a standard, an overhanging arm carried by said standard, a needle bar mounted in the outer end of said overhanging arm, a needle carried thereby, a shaft mounted in said overhanging arm and devices actuated by said shaft for operating the needle bar, a horizontal arm mounted on said standard, a work supporting arm carried by the horizontal arm and having its free end extending underneath the overhanging arm, a main shaft mounted in said horizontal arm, means for actuating said shaft in the overhanging arm from said main shaft, complementary stitch forming mechanism located in said work supporting arm and devices for operating said complementary stitch forming mechanism from said main shaft.

5. A sewing machine including in combination, a standard, an overhanging arm carried by said standard, a needle bar mounted at the outer end of said overhanging arm, a needle carried thereby, thread laying devices coöperating with the needle, a horizontal arm carried by said standard, a work supporting arm suspended therefrom and having its free end extending underneath the overhanging arm, a main shaft mounted in said horizontal arm, devices operated by said main shaft for actuating said needle bar and said thread laying devices.

6. A sewing machine including in combination, a standard, an overhanging arm carried by said standard, a needle bar mounted at the outer end of said overhanging arm, a needle carried thereby, thread laying devices coöperating with the needle, a horizontal arm carried by said standard, a work supporting arm suspended therefrom and having its free end extending underneath the overhanging arm, a main shaft mounted in said horizontal arm, devices operated by said main shaft for actuating said needle bar and said thread laying devices, complementary stitch forming mechanism located in said work supporting arm and devices operated by said main shaft for actuating said complementary stitch forming devices.

7. A sewing machine including in combination, a standard, an overhanging arm carried by said standard, a needle bar mounted at the outer end of said overhanging arm, a needle carried thereby, thread laying devices coöperating with the needle, a horizontal arm carried by said standard, a work supporting arm suspended therefrom and having its free end extending underneath the overhanging arm, a main shaft mounted in said horizontal arm, devices operated by said main shaft for actuating said needle bar and said thread laying devices, complementary stitch forming mechanism located in said work supporting arm and devices operated by said main shaft for actuating said complementary stitch forming devices.

tal arm carried by said standard, a work supporting arm suspended therefrom and having its free end extending underneath the overhanging arm, a main shaft mounted in said horizontal arm, devices operated by said main shaft for actuating said needle bar and said thread laying devices, a looper located in said work supporting arm and coöperating with said needle, and devices operated by said main shaft for actuating said looper.

8. A sewing machine including in combination, a standard, an overhanging arm carried by said standard, a needle bar mounted at the outer end of said overhanging arm, a needle carried thereby, thread laying devices coöperating with the needle, a horizontal arm carried by said standard, a work supporting arm suspended therefrom and having its free end extending underneath the overhanging arm, a main shaft mounted in said horizontal arm, devices operated by said main shaft for actuating said needle bar and said thread laying devices, a looper mounted in said work supporting arm and coöperating with said needle, a feed dog located at the outer end of said work supporting arm, a feed bar carrying said dog, and devices operated by said main shaft for actuating said looper and said feed bar.

9. A sewing machine including in combination, a standard, an overhanging arm carried by said standard, a needle bar mounted at the outer end of said overhanging arm, a needle carried thereby, thread laying devices coöperating with the needle, a trimming mechanism, a horizontal arm carried by the standard, a work supporting arm suspended therefrom and having its free end extending underneath the overhanging arm, a main shaft mounted in said horizontal arm, and devices operated by said main shaft for actuating the needle, said thread laying devices and the trimming mechanism.

10. A sewing machine including in combination, a standard, an overhanging arm carried by said standard, a needle bar mounted at the outer end of said overhanging arm, a needle carried thereby, an arm projecting forwardly from said standard, a horizontal arm carried thereby and extending in a direction parallel to the overhanging arm, a work supporting arm carried by the horizontal arm and having its free end extending underneath the free end of the overhanging arm, a main shaft in said horizontal arm, and devices operated from one end of said shaft for reciprocating said needle, complementary stitch forming mechanism located in said work supporting arm, a feeding device in said work supporting arm, and devices oscillated by the other end of said main shaft for operating the complementary stitch forming mechanism and said feeding device.

11. A sewing machine including in combination a standard, an overhanging arm carried by said standard, a needle bar mounted at the outer end of said overhanging arm, a needle carried thereby, an arm projecting forwardly from said standard, a horizontal arm carried thereby and extending in a direction parallel to the overhanging arm, a work supporting arm carried by the horizontal arm and having its free end extending underneath the free end of the overhanging arm, a main shaft mounted in said horizontal arm and projecting through said forwardly projecting arm carried by the standard, a belt wheel on the outer end of said shaft, an oscillating shaft in said overhanging arm, means operated thereby for reciprocating the needle, and means for oscillating said shaft from said main shaft in the horizontal arm.

12. A sewing machine including in combination a standard, an overhanging arm carried by said standard, a needle bar mounted at the outer end of said overhanging arm, a needle carried thereby, an arm projecting forwardly from said standard, a horizontal arm carried thereby and extending in a direction parallel to the overhanging arm, a work supporting arm carried by the horizontal arm and having its free end extending underneath the free end of the overhanging arm, a main shaft mounted in said horizontal arm and projecting through said forwardly projecting arm carried by the standard, a belt wheel on the outer end of said shaft, an oscillating shaft in said overhanging arm, means operated thereby for reciprocating the needle, means for oscillating said shaft from said main shaft in the horizontal arm, a looper mounted in the work supporting arm, a looper shaft supporting said looper, a feed dog in said work supporting arm, a feed bar carrying said feed dog, and devices actuated by said main shaft for operating the looper shaft and the feed bar.

13. A sewing machine including in combination, a standard, an overhanging arm carried thereby, a shaft mounted in said overhanging arm, a needle bar at the outer end of said overhanging arm, a needle carried thereby, means for reciprocating said needle bar from said shaft, a trimming mechanism mounted at the outer end of said overhanging arm and including a fixed trimming blade and a movable trimming blade, a thread laying device at the outer end of said overhanging arm coöperating with said needle, an oscillating member, means for oscillating the same from said shaft, said thread laying device being carried by said oscillating member, an eccentric mounted on said oscillating member, and means actuated thereby for oscillating the movable trimming blade.

14. A sewing machine including in combination, a standard, an overhanging arm, a shaft mounted in said overhanging arm, means for oscillating said shaft, a needle bar at the outer end of said overhanging arm, a needle carried thereby, an arm carried by said shaft and connected to the needle bar for reciprocating the same, a thread laying device coöperating with the needle, an oscillating member carrying said device, an arm carried by said shaft and connected to said member for oscillating the same, a trimming mechanism including a movable trimmer blade, and means for oscillating said movable trimmer blade from said oscillating member.

15. A sewing machine including in combination, a standard, an overhanging arm, a shaft mounted in said overhanging arm, means for oscillating said shaft, a needle bar at the outer end of said overhanging arm, a needle carried thereby, an arm carried by said shaft and connected to the needle bar for reciprocating the same, a thread laying device coöperating with the needle, an oscillating member carrying said device, an arm carried by said shaft and connected to said member for oscillating the same, a trimming mechanism including a movable trimmer blade, an eccentric carried by said oscillating member, and devices actuated thereby for oscillating said movable trimmer blade.

16. A sewing machine including in combination, a standard, an overhanging arm carried thereby, a needle bar mounted at the outer end of said overhanging arm, a needle carried thereby, an arm projecting forwardly from said standard, a horizontal arm carried thereby, a depending post at the outer end of said arm, a work supporting arm at the lower end of said post, said work supporting arm extending in a direction at an angle to the plane of the overhanging arm and having its free end underneath said overhanging arm, a main shaft mounted in said horizontal arm, devices operated thereby for actuating the needle bar, a feed dog in said work supporting arm, a feed bar carrying the same, a looper in said work supporting arm, a looper support for said looper, an eccentric member on said main shaft, devices actuated thereby for moving the looper support endwise and for moving the feed bar back and forth, a second eccentric on said main shaft, and devices operated thereby for oscillating the looper support and for raising and lowering the feed bar.

17. A sewing machine including in combination, a standard, an overhanging arm carried thereby, a needle bar mounted at the outer end of said overhanging arm, a needle carried thereby, an arm projecting forwardly from said standard, a horizontal arm carried thereby, a depending post at the

outer end of said arm, a work supporting arm at the lower end of said post, said work supporting arm extending in a direction at an angle to the plane of the overhanging 5 arm and having its free end underneath said overhanging arm, a main shaft in said horizontal arm, said main shaft projecting over the post at one end thereof and projecting through the forwardly projecting arm at the 10 other end thereof, a belt pulley on said shaft adjacent said standard, a looper in said work supporting arm, a looper shaft carrying said looper, a feeding device in said work supporting arm, a feed bar carrying said feeding device, an eccentric on said main shaft, devices located in said 15 post and operated by said eccentric for moving said looper shaft endwise and for reciprocating the feed bar, a second eccentric on the main shaft, and devices in said post coöperating with 20 said last-named eccentric for oscillating the looper supporting shaft.

18. A sewing machine including in combination, a standard, an overhanging arm carried thereby, a needle bar mounted at the outer end of said overhanging arm, a needle carried thereby, an arm projecting forwardly from said standard, a horizontal arm carried thereby, a depending post at 25 the outer end of said arm, a work supporting arm at the lower end of said post, said work supporting arm extending in a direc- 30

tion at an angle to the plane of the overhanging arm and having its free end underneath said overhanging arm, a main shaft 35 in said horizontal arm, said main shaft projecting over the post at one end thereof and projecting through the forwardly projecting arm at the other end thereof, a belt pulley on said shaft adjacent said standard, a looper in said work supporting arm, a looper shaft carrying said looper, a feeding device in said work supporting arm, a feed bar carrying said feeding device, an eccentric on said main shaft, devices located in said 40 post and operated by said eccentric for moving said looper shaft endwise and for reciprocating the feed bar, a second eccentric on the main shaft, devices in said post coöperating with said last-named eccentric for oscillating the looper supporting shaft, an oscillating shaft in the overhanging arm, means actuated thereby for reciprocating the needle bar, an eccentric member on said main shaft adjacent the belt wheel, and a pitman 45 actuated by said eccentric member and connected to said shaft in the overhanging arm for oscillating the same.

In testimony whereof, I affix my signature in the presence of two witnesses.

DUDLEY S. SEYMOUR
